Patented Apr. 22, 1958

182,572

TROPHY BASE

Ray E. Dodge, Miami Beach, Fla., and
Michael J. Albanese, Chicago, Ill.

Application August 16, 1957, Serial No. 47,396

Term of patent 14 years

(Cl. D29—23)

FIG. 1

FIG. 2

Fig. 2 is a side elevational view; and

Fig. 3 is a top plan view thereof.

The back of the article is substantially plain.

We claim:

The ornamental design for a trophy base, as shown and described.
